UNITED STATES PATENT OFFICE

161,801

WARMING BAG OR THE LIKE

Verne L. Stephenson, Goshen, Ind., assignor to Snuggle Products, Inc., Goshen, Ind., a corporation of Indiana

Application February 23, 1949, Serial No. 1,018

Term of patent 14 years

(Cl. D92—2)

To all whom it may concern:

Be it known that I, Verne L. Stephenson, a citizen of the United States, residing at Goshen, in the county of Elkhart and State of Indiana, have invented a new, original, and ornamental Design for a Warming Bag or the like, of which the following is a specification, reference being had to the accompanying drawing, forming part thereof.

Fig. 1 is a front elevational view of a warming bag, showing my new design.

Fig. 2 is a rear elevational view of the same.

I claim:

The ornamental design for a warming bag or the like, substantially as shown.

VERNE L. STEPHENSON.
